UNITED STATES PATENT OFFICE.

ANDREW C. CAMPBELL, OF WATERBURY, CONNECTICUT, ASSIGNOR TO THE E. J. MANVILLE MACHINE COMPANY, OF WATERBURY, CONNECTICUT, A CORPORATION OF CONNECTICUT.

METAL-HEADING MACHINE.

No. 926,170.

Specification of Letters Patent.

Patented June 29, 1909.

Application filed January 10, 1908. Serial No. 40,194.

To all whom it may concern:

Be it known that I, ANDREW C. CAMPBELL, a citizen of the United States, residing at Waterbury, in the county of New Haven and 5 State of Connecticut, have invented a new and useful Metal-Heading Machine, of which the following is a specification.

This invention relates to a machine known as a direct acting multiple stroke open die 10 header, and which is provided for heading bolt, screw or other blanks that are longer than can be successfully headed in a solid die machine and that require more than one stroke for expanding the metal sufficiently 15 to produce the desired head. In this type of machine a continuous length of wire is fed by grooved rolls, operated at proper intervals by a crank actuated ratchet and pawl mechanism, through ordinary square dies of suitable size and length against a swinging stop. 20 After the wire has been fed against the stop the dies are forced sidewise so as to sever the wire and carry the blank thus produced into line with punches held by a carrier which is 25 raised and lowered at the proper time on the end of the gate which is reciprocated by a crank. The dies are forced sidewise and squeezed together so as to strongly grip the blank by a toggle mechanism that is actuated 30 by a lever and cam. The exposed end of the blank is operated upon by one punch for the purpose of coning or gathering the stock centrally, and then by the other punch for finishing the head to the required shape. As 35 the second punch recedes the grip is released and the dies loosely holding the blank returned sidewise into line with the feed so that the length of wire next fed ejects the piece which has been headed. After the first 40 blank is ejected and before the feeding is completed the stop swings into line and determines the length of wire fed, and consequently the exact amount of metal which shall be compressed into the head of the 45 blank.

It is indispensable where exactness of product is required that the machine have great power and rigidity to resist, not only the longitudinal stress of the heading, but also 50 the lateral strain exerted by the powerful toggle mechanism which holds the dies together as the metal tends to swell during the heading operation. There must also be an

accurate feed as variation in the lengths of the blanks causes irregularity in the heads. 55 All parts of the machine must be accessible, and the adjustments convenient, and in order to be practicable, that is, a commercial success, the strong and powerful mechanisms must be so designed and combined as to be 60 durable and permit of rapid and exact action.

The object of this invention is to produce a strong, powerful, durable, rapid and convenient heading machine which can be conveniently and accurately adjusted, which will 65 feed the exact amount of stock, which feed can be started and stopped when desired, but in such manner that this cannot be done at the wrong time so as to cause damage to the parts or the production of short blanks, and 70 which will release the powerful mechanisms in case of improper feeding or jamming of the wire, or accidental introduction between the dies of parts of foreign matter, and will 75 automatically stop the feeding in case of any such irregular feeding or jamming, and thus prevent the parts from becoming broken, strained or injured.

Figure 1 of the accompanying drawings shows a plan of a machine which embodies 80 this invention. Fig. 2 shows an elevation of the side of the machine upon which are the operating mechanisms for feeding the wire and moving and clamping the dies. Fig. 3 shows a transverse section of the bed on the plane indicated by the dotted line 3—3 on Fig. 1. Fig. 4 shows a plan of a portion of the bed which is shown in Fig. 3 with the dies and die holder removed. Fig. 5 shows a central, vertical longitudinal section of the 85 machine. Fig. 6 shows a plan on larger scale of a portion of the toggle actuating mechanism. Fig. 7 shows a side elevation of the same. Fig. 8 shows a plan of a portion of the bed with the die holding cover moved backwardly so as to expose the dies and die blocks on the bed. Fig. 9 shows a plan of the toggle mechanism. Fig. 10 shows a side view of a toggle. Fig. 11 shows a side view of a toggle block. Fig. 12 shows a blank as 100 it is after it has been severed from the continuous length of wire, and before it has been subject to the action of a punch; the blank after it has been subjected to the action of the first punch; and the blank after it has 105 been acted upon by the second punch, and is

ready to be ejected from the machine. Fig. 13 shows a plan of the feed pawl and the mechanism by which it is carried into and out of effective position. Fig. 14 shows a 5 side elevation of the same. Fig. 15 shows the effective position of the feed pawl. Fig. 16 shows the connection between the pawl frame and the link by which it is oscillated. Fig. 17 shows a side view of the stop and 10 its adjusting mechanism. Fig. 18 shows a plan of the stop. Fig. 19 shows the stop adjusting mechanism. Fig. 20 shows an end 15 view of the dies and the means for separating them. Fig. 21 shows a modified form of stop adjusting mechanism. Fig. 22 shows a modified mechanism for operating the pawl lever.

The fly wheel 1 is held on the outer end of the crank shaft 2 between friction collars 3, which are forced together by wedge keys 4 20 driven through mortises in the shaft. (Fig. 1.) This connection, while holding the fly wheel rigid enough to transmit sufficient power for regular work, will, in case of sudden stopping of the machine, allow the fly wheel to 25 turn between the clamping collars, and thus relieve the shock which would otherwise tend to break or injure the machine. This construction also facilitates the removal of the wheel when necessary.

30 One end of the pitman 5 embraces the crank 6 on the crank shaft, and the opposite end has a bearing in a joint block 7 pocketed in the horizontally movable gate 8. The gate on its forward end carries a head 9 which is 35 adjustable sidewise. Movable vertically in this head is a punch holder 10, carrying punches 11 and 12. (Figs. 1, 5.) The rotation of the crank through the pitman and joint block reciprocates the gate bearing the 40 head with the punch holder and punches toward and from the dies.

On the lower end of the punch holder is a 45 plate 13 which is engaged by the arms 14 of a rocker shaft 15 (Fig. 5). This rocker shaft has a rocker arm 16 which is engaged by the 50 end of a yoke 17 that is reciprocated by a cam 18 on the cam shaft 19, which is supported by the frame of the machine below the crank shaft. (Figs. 1, 5.) The reciprocation of this yoke rocks the shaft and oscillates the arms in such manner that at the proper time, the punch holder is raised and lowered to bring the punches alternately in line with the blank in the dies. The details 55 of the connections and means for adjusting these parts, which reciprocate and raise and lower the punches, are not described in full, as they are not essential to the invention claimed herein.

60 On the end of the crank shaft distant from the fly wheel, is a pinion 20 which meshes with a gear 21 on the end of the cam shaft. (Figs. 1, 2.) As the machine shown is a double stroke machine, the pinion and gear 65 are in the ratio of one to two, so that the cam

shaft will make one rotation to two rotations of the crank shaft, and consequently the punches will be reciprocated once in their upper, and once in their lower position to each movement of the feed and dies. Standard dies 22 of the rectangular type, with a portion of the opening in each section, and of lengths to suit the blanks to be acted upon, are laid side-by side in a pocket in the end of the frame on a hardened steel plate 23 (Figs. 70 75 3, 5, 20). Back of the die blocks to take the heading blows is a plate 24. The wire is fed to the dies through a bushing 25 in the frame (Figs. 5, 8). The dies when forced sidewise shear off the wire.

80 Solid integral sections of the frame form the back, sides and bottom of the pocket, as shown in Fig. 4 so as to resist both the longitudinal heading blows imparted by the punches, and the transverse gripping strains 85 produced by the powerful mechanism which holds the die sections together while the heading takes place.

Over the top of the dies and holding them 90 down securely is a cover 26. The cover has channels in its sides that fit and slide on guides 27, on the side walls of the pocket. (Figs. 1, 3, 5, 8.) When this cover is unfastened it may be slid toward the gate so as to uncover and expose the dies allowing 95 them to be readily removed and changed without requiring the removal of a heavy die block. Attached to the front of the cover are plates 260 which confine the dies longitudinally in the recess.

100 The dies are forced sidewise transversely of the machine for severing the wire and carrying the blank into line with the punches by the head 28 of plungers 29 that are moved through the side of the frame by toggles 30. (Figs. 1, 3, 9.) The outer toggle arms are backed by a plate 31 that is adjusted in the frame by a wedge 32, the position of which is determined by the screws 33 (Figs. 1, 3, 8). The joints of the toggles are arranged in 110 blocks 34 which are placed in an opening in a slide 35 that is movable back and forth in an opening in the frame. (Figs. 1, 9.)

115 The outer end of the slide 35 is hinged to a yoke 36, which is connected with a link 37 that is hinged with the upper end of an angle lever 38, which is mounted on a rocker shaft 39 (Figs. 1, 2, 6, 7). The angle lever has a roll 40, which is engaged by the face of a cam 41 on the cam shaft and a roll 42, 120 which is engaged by the cam 43 on the interior of the gear 21 on the cam shaft (Figs. 2, 6, 7). The cam 41 lifts the end of the angle lever and forces the link, yoke and slide forwardly in such manner as to straighten the 125 toggles and cause the plungers to force the dies transversely of the machine. The cam 43 depresses the end of the angle lever and this, through the link, yoke and slide bends the toggles and thus relieves the lateral ten- 130

sion on the dies. As the cam shaft makes but one revolution to two revolutions of the crank shaft, the dies by this mechanism are moved sidewise once to each two reciprocations of the punches.

The connection between the yoke 36 and the link 37 is made in such a manner that if the wire is not properly held between the dies, or it becomes jammed or any other matter gets between the dies so that they cannot properly close, the connection will break and relieve the pressure so that the machine will not be damaged. This is accomplished by providing the head of the link 37 with a fork 44 that will thrust against a brittle plate 45 placed in the opening in the yoke between the fork and stud 46 screwed into the yoke (Fig. 6). The stud is set up so as to hold the plate firmly against the end of the fork. This ordinarily makes a tight connection between the yoke and the link of sufficient strength to accomplish the required work, but should the dies become jammed so that the toggles cannot yield when the lever forces the yoke forwardly, the ends of the fork will break the plate 45 over the stud 46. When this plate breaks, the connection between the link and yoke is loosened so the lever will oscillate and move the link freely back and forth in the yoke without moving the yoke and imparting any force to the toggles.

When transverse pressure on the dies is relieved by bending the toggles, the dies are pushed back to their original position in line with the feed opening through the frame, by a plunger 47 with a T shaped head 48, which is thrust against the side of one of the die sections by a spring 49, that is fastened to the side of the machine opposite to the side bearing the toggles (Figs. 1, 3, 8). The dies are pushed parallel to their original position, after the pressure is released, by the T shaped head of the plunger, and thus are not liable to stick and become deranged.

When the dies are returned to position in front of the feed opening and the toggle pressure is relieved, they are spread apart so as to release their grip upon the blank which has been shaped, by the tapered ends of plungers 50 that are forced downwardly through openings in the sliding cover above the dies by springs 51 that are fastened to the top of the frame. (Figs. 1, 3, 5, 20.)

The wire is fed into the machine by grooved feed rolls 52, which are fastened to shafts 53 that are provided with intermeshing gears 54. The upper feed roll shaft is supported by a yoke 55, which is movable up and down in the frame 56, which supports the lower feed roll shaft and is bolted to the front end of the frame. The upper shaft is forced downwardly to give just the right amount of tension between the feed rolls by a screw 57 on the hand wheel 58 in a common manner,

which is not illustrated in detail as it forms no essential feature of the invention claimed herein. (Figs. 1, 2.)

Fixed on the end of the lower feed roll shaft, adjacent to the gear is a ratchet wheel 59. A pawl 60, carried by a block 61 pivoted to the arm 62 is arranged to engage the ratchet teeth. (Figs. 1, 2, 13, 15.) The arm 62 is loosely mounted on the end of the lower feed roll shaft and is connected by a long rod 75 or link 63 with a crank pin 64 projecting from a block 65 that is adjustably mounted in a groove in the crank disk 66, which is fastened to the pinion on the end of the crank shaft (Figs. 1, 2). The rotation of the crank shaft through the link oscillates the pawl arm and causes the pawl when it engages the teeth of the ratchet wheel to rotate the feeding rolls with an intermittent motion, and feed the wire intermittently through the end of the frame to the dies. This causes the wire feed to take place during one-half a revolution of the crank shaft, and compels the pawl to pass twice in each direction of its arc of motion during the heading of each blank. 90

To prevent the wire from being fed twice during the heading of each blank, the pawl is lifted at every other revolution of the crank shaft so that it will not engage the teeth of the ratchet, by means of the curved face of 95 the lever 67, that extends beneath a roll 72 on the side of the pawl. (Figs. 1, 2, 13, 15.) This lever is mounted on a rocker shaft 68 that bears an angle lever 69 which has one end connected by a link 70 with an arm 71 100 formed on the lever 38, which is rocked to open and close the toggles and cause the sliding movement of the dies. (Figs. 1, 2.) As the toggle lever is swung downwardly by the cam on the gear, the arm 71 causes the link 105 to rock the angle lever 69 and rocker shaft 68 in such manner that the end of the lever 67 is lowered so that the pawl can engage the ratchet teeth, and cause the rolls to feed the wire. When the toggle lever is swung up- 110

wardly and the toggles force the dies sidewise, the link pushes forward the lower end of the angle lever 69, and causes the pawl lever to lift so that it engages the pawl roll and prevents the pawl during its next forward movement from engaging the ratchet teeth. This mechanism allows the pawl to engage the ratchet teeth only every other time it is oscillated, consequently, although the feeding of the wire is accomplished from 115 the crank shaft during one-half a revolution of that shaft, it takes place during only one-quarter of a revolution of the cam shaft, which is the correct time for feeding. The angle lever 69 which lifts the pawl lever 67 120 instead of being connected by the link 70 with the lever 38 may be engaged by a cam 103 formed on a block 104 that is attached directly to the end of the toggle slide 35. (Fig. 22.) 130

Pivoted to the feed roll supporting frame and extending over the roll shafts, within easy reach of the operator, is a handle 73. On the lower end of the shaft 74, to which this handle is attached, is a lever 75 which has an upwardly extending lug 76 that is normally engaged by the hooked end of a spring latch 77 which is pivoted to the toggle supporting frame in such manner as to prevent the handle from being moved until the latch is unhooked (Figs. 1, 2, 13, 14).

The end of the lever that projects from the lower end of the handle shaft, when in normal position extends above the end of an arm of the angle lever 69 on the shaft which carries the lever that is designed to lift the pawl from engagement with the ratchet teeth. When the handle is in the position shown in the drawings, and the lever 75 extends over the end of the lever 69, the pawl lever 67 is raised to such a position that the pawl when oscillated is held above and does not engage the ratchet teeth. The latch 77 carries a screw 79 which is adjusted to be engaged by a stud 80 on the end of the toggle slide, when the toggle slide is at the forward limit of its movement and to push the latch forwardly out of engagement with the lug 76 on the lever 75, so that the handle may be turned and the lever moved from above the upper arm of the angle lever 69. (Figs. 13, 14.) When the parts are in this relation, the pawl lifting lever can drop so that the pawl will then engage with the teeth of the ratchet and cause the rolls to feed. This mechanism prevents the handle from being pushed at the wrong time, that is, the handle cannot be pushed for allowing the pawl to engage the feed ratchet until the dies are in the proper position to receive the wire which is fed by the rolls. On the contrary, the handle cannot be moved so that the lever 75 will be swung above the arm of the lever 69 to cause the feeding to stop until the arm is depressed and the pawl is lifted during its normal operation. In other words, the operator cannot throw the feed pawl out or in except at the proper instant. At all other times during the revolution of the machine the handle is automatically locked against movement.

The link 70 which connects the arm of the angle lever 69 that rocks the pawl lever up and down and the angle lever 38 that reciprocates the toggle slide is slotted at each end (Figs. 2, 7, 14). A pin 81 projects from the lower arm of the lever 69 into a slot in the end of the link, and a spring 82 connected with the lower end of this lever and a pin 83 that projects from the frame beneath the toggles tends to draw the lower end of the lever backwardly so that the pin normally remains in the rear end of the slot in the link. This spring also tends to depress the pawl lifting lever (Figs. 2, 14). The other

end of the link 70 is also slotted and is connected with the arm 71 of the lever 38 by a pin 84 that extends into the slot and a spring 85 arranged between the pin and a collar 86 on the link. This tends to hold the link upwardly, that is, with the pin at the lower end of the slot. (Figs. 2, 7.) The springs 82 and 85 have such tension that under normal conditions the link, as it reciprocates, oscillates the angle lever and raises and lowers the pawl lifting lever 67 at the proper time, as if the link were joined solidly with the lever 69 and arm 71.

Pivoted to the under side of the yoke 36 that is attached to the end of the toggle slide is a weighted lug 87. A catch 88 connected with the fork 44 in the yoke normally holds this weighted lug lifted, as shown in full lines in Fig. 7. When the plate 45 is broken as the result of any jamming of the machine so that the angle lever will oscillate freely without moving the toggle slide, this catch becomes disengaged from the weighted lug, and allows the lug to drop down to the position shown in dotted lines in Fig. 7. When this lug is in this position and the toggle remains stationary, the next upward and rearward movement of the end of the link 70 as the lever 38 continues to oscillate, brings the end of the link into engagement with the end of the lug, and causes the link to be forced downwardly on the pin 84 which connects it with the lever. When the link is forced downwardly, the distance between the end, which is thus connected with the lever, and the other end, which is connected with the pawl lifting angle lever is increased sufficiently so that while the pawl lifting lever will continue to be raised and lowered by the oscillation of the angle lever 38, the moving path of the pawl lifting lever will be so much above its normal plane that the pawl will not under any circumstances engage the ratchet teeth and feed the wire. In other words, if the dies become jammed sufficiently to cause the safety plate to become broken and release the toggle, the feed will be stopped at the same time.

The wire stop arm 89 is mounted on an arbor 90 that extends through the front of the frame. On one portion of the hub of the wire stop arm are gear teeth 91 engaging with which are teeth 92 on the rack bar 93. (Figs. 3, 5.) This rack bar is engaged by a lever 94 which is pivoted to the frame and is oscillated by a cam 95 on the cam shaft. (Figs. 1, 5.) This cam is so timed that the wire stop arm is oscillated in front of the opening in the dies, through which the wire is fed, just after a finished blank has been ejected and just before the feeding of the wire for a new blank is completed, in order that the end of the wire strike the stop and the exact amount be fed through the dies for forming the required head. It is desirable

that the feed rolls shall tend to feed a little more than enough to advance the required amount of wire, their tension being such on the wire that when the end engages the stop 5 and the required amount is fed the rolls will slip on the wire. By this means the exact amount of wire will be fed each time.

The front end of the stop arbor passes through a bushing 96, which is threaded in 10 the end of the frame in such manner that by turning the bushing the arbor and stop can be adjusted longitudinally. The bushing 96 also has spiral teeth 97 on the outside of the frame, and engaging with these is a worm 98, 15 on the lower end of a vertical shaft 99, which is supported by the feed roll frame and is provided with a hand wheel 100 above the frame (Figs. 5, 17, 18, 19). By turning this hand wheel, the longitudinal position and 20 consequently the distance of the face of the stop from the ends of the dies can be adjusted with great exactness while the machine is in operation.

If desired the bushing 101 supporting the 25 outer end of the stop arbor 90 may be fitted to slide longitudinally and its position may be determined by a screw 102 for the purpose of adjusting the stop toward and from the feed opening. (Fig. 21).

30 In this machine the feed operating mechanism, as well as the grip operating mechanism, is on the side of the machine opposite the fly wheel. This leaves the front corner of the machine on the fly wheel side free of 35 mechanism so the operator can readily see and conveniently reach all parts around the dies. The feed is started by pushing the handle, which cannot be done except when the parts are in the right relation to 40 feed a blank of proper length, consequently, short blanks cannot be fed, nor will the feed occur at such time that the mechanisms will become jammed. The gripping mechanism, that is the cam actuated toggles, are substantial and powerful. The frame is most 45 rigid, and the crank imparts a most powerful and efficient movement to the gate which carries the punches. The form of the frame and the movable cover for the dies obviates 50 the necessity of separate die blocks, and while it insures the frame against springing either under the lateral gripping pressure or the longitudinal punching force, it permits the dies to be quickly reached for inspection 55 and change if desired, without the removal of a heavy die block. The stop can be quickly adjusted while the machine is in motion, so that the exact amount of metal can be fed through the dies for producing a perfect head on the blank, and in case of jamming of the parts or the introduction of foreign matter between the dies, the gripping pressure is relieved and the feed is stopped. 60 The dies are returned opposite the feed opening by a single plunger, but in such manner

that they move parallel and without danger of jamming and they are supported so that the blank can be easily ejected by the feeding in of the next length of wire. The wire stop shaft is firmly supported in solid metal below 70 the dies, very close to the axis of the feed, so that the amount of wire fed will always be the same. The toggles which force the dies sidewise for severing the wire and gripping it, are easily and quickly adjusted, and while 75 the pawl is operated from the crank shaft at each revolution of the crank, it is not allowed to engage the ratchet wheel for feeding the wire, except at every other revolution of the crank, consequently the feed is positive and 80 quick and yet at the proper time.

The invention claimed is:

1. The combination with dies for holding blanks of, means for causing the dies to grip the blanks, such means having a yoke, a fork 85 loosely connected with the yoke, an adjustable stud carried by the yoke, and a breakable plate engaging the fork and engaged by the stud for holding the yoke and fork rigid with relation to each other under normal 90 strains, substantially as specified.

2. In a header in combination, a reciprocating gate, means for reciprocating the gate, a punch carried by the gate, dies for holding the blanks, means for causing the dies to grip 95 the blanks, a lever for operating said means, a connection between said lever and said means, adapted to become released when abnormal resistance is offered to said means, rolls for feeding blanks to the dies, a ratchet 100 and pawl mechanism for operating said rolls, means for actuating the ratchet and pawl mechanism, means for preventing the ratchet and pawl mechanism from operating the feed rolls, and means released by the release of 105 the connection between the lever and the die operating means for bringing into action the means which prevents the normal action of the ratchet and pawl mechanism, substantially 110 as specified.

3. In a header in combination, dies for holding the blanks, mechanism for closing the dies, a connection in said mechanism which becomes released when abnormal resistance is offered to the closing of the dies, rolls for 115 feeding blanks to the dies, mechanism for operating the rolls, means for preventing the normal action of the roll operating mechanism, a connection between said preventing means and the mechanism for closing the 120 dies, and means adapted to be released by the first mentioned connection when that connection is released by abnormal resistance, to engage the second mentioned connection and to bring into action the means for preventing the roll operating mechanism from 125 acting, substantially as specified.

4. In a header in combination, a reciprocating gate, a punch carried by the gate, dies for holding the blanks, toggles for closing the 130

dies, a lever for operating the toggles, a breakable connection between said lever and the toggles, rolls for feeding blanks to the dies, a ratchet and pawl mechanism for actuating the rolls, a lever arranged to prevent the pawl from engaging the ratchet, means connected with the toggle lever for oscillating the said pawl disengaging lever, and means released by the breaking of the connection between the toggle lever and the toggles, adapted to engage the connection between the toggle lever and the pawl lever in such manner as to cause the said connection to oscillate the pawl lever in such position that the pawl is prevented from engaging the ratchet, substantially as specified.

5. In a header in combination, a gate, a punch carried by the gate, dies for holding blanks, toggles for causing the dies to grip the blanks, a slide for operating the toggles, a lever for operating the slide, a connection between said lever and said slide, rolls for feeding blanks to the dies, a ratchet and pawl mechanism for intermittently rotating the feed rolls, means for holding the pawl disengaged from the ratchet, a lever arranged to cause said means to hold the pawl out of engagement with the ratchet, a latch arranged to engage said lever, and means operated by the toggle slide for causing the latch to unlock said lever at the proper time, substantially as specified.

6. In a header in combination, a reciprocating gate, a punch carried by the gate, dies for holding blanks, means for causing the dies to grip the blanks, rolls for feeding blanks to the dies, mechanism for intermittently rotating the rolls, means for preventing the roll feeding mechanism from operating, a latch arranged to prevent said means from operating, said latch being arranged to release said means by the movement of the means which causes the dies to grip the blank, substantially as specified.

45 7. In a header in combination, a gate, a punch carried by the gate, dies for holding the blanks, toggles for causing the dies to grip the blanks, a slide for operating the toggles, means for actuating the slide, rolls for feeding blanks to the dies, a ratchet and pawl mechanism for intermittently rotating the feed rolls, a lever for preventing the pawl from engaging the ratchet, an arm adapted to rock said lever into a plane which will prevent the pawl from engaging the ratchet, a lever adapted to engage said arm and prevent it from moving, a latch normally holding said lever, a handle adapted to move said

lever when the latch is released, and means carried by the toggle slide for causing the latch to release the lever so that by means of the handle the lever may be moved into position to hold the pawl lever in the desired plane for preventing feeding, or for causing feeding by the feed rolls, substantially as specified.

8. In a header in combination, a reciprocating gate, means for reciprocating the gate, a frame supporting the gate and said actuating means, said frame having a recess in the end opposite the gate, which recess has integral end, side and bottom walls, dies for holding blanks located in said recess, a cover for the dies movable longitudinally in the recess, plates attached to and movable with the cover for holding the dies, means for feeding blanks to the dies, and means for causing the dies to grip the blanks and move them sidewise, substantially as specified.

9. In a header in combination, a reciprocating gate, means for reciprocating the gate, a frame supporting the gate and said actuating means, said frame having a recess in the end opposite the gate, which recess has integral end, side and bottom walls, dies movable in said recess, means for causing the dies to grip the blanks and move them sidewise, a cover movable above the dies, toward and from the gate for holding the dies in position for releasing them so that they may be removed from the recess, and means for feeding blanks to the dies, substantially as specified.

10. In a header in combination, a supporting frame having a recess with integral end, side and bottom walls, a cover for said recess movable longitudinally in the frame, dies located in said recess and held by said integral walls and movable cover, and means for moving the dies laterally in said recess beneath the cover, substantially as specified.

11. In a header in combination, a gate, a punch carried by the gate, dies for holding blanks, means for causing the dies to grip the blanks, rolls for feeding blanks to the dies, a ratchet and pawl mechanism for intermittently rotating the feed rolls, means for holding the pawl disengaged from the ratchet, means for locking the pawl disengaging means, and means operated by the moving means for unlocking the means which lock the pawl disengaging means, substantially as specified.

ANDREW C. CAMPBELL.
